UNITED STATES PATENT OFFICE.

MAX O. CLAUSS, OF NEW YORK, N. Y., ASSIGNOR TO THE CLARK THREAD COMPANY, OF NEWARK, NEW JERSEY, A CORPORATION OF NEW JERSEY.

METHOD OF WINDING SKEINS.

1,401,515.

Specification of Letters Patent. Patented Dec. 27, 1921.

Application filed August 1, 1919. Serial No. 314,647.

To all whom it may concern:

Be it known that I, MAX OTTO CLAUSS, a citizen of Germany, and a resident of New York, in the county of New York and State 5 of New York, having invented certain new and useful Improvements in Methods of Winding Skeins, do hereby declare that the following is a full, clear, and exact description of the same.

10 This invention relates to an improved method of winding skeins. It is one object of the present invention to provide an improved method of winding yarn, cotton or silk thread into skeins, whereby the natural 15 tendency of the thread, and especially coarse yarns, to twist upon itself when the skein is loosened, is eliminated.

Another object of my invention resides in the provision of an improved method of 20 winding yarn or thread into skeins whereby a continuous thread of relatively great length is formed into a comparatively short skein.

The invention has for a further object to 25 provide a method of winding skeins in which the thread is wound to form main or primary and intermediate or subsidiary loops disposed in superposed relation and so arranged that said loops may be readily 30 separated without entangling the yarn or thread.

Another object of the invention is to wind 35 the skein in such manner that it will be unwindable without entanglement simply by pulling on or drawing out the proper 40 thread or strand, whether the skein is in the condition in which it comes from the winding machine composed of the main or primary loops and the plurality of intermediate or subsidiary loops, or whether the skein is unfolded into a single series of simple loops by separating the intermediate or subsidiary loops from the main or primary loops.

45 With the above, and other objects in view, the invention consists in the improved method of winding skeins, as above characterized, and in the several steps thereof as will be hereinafter more fully described, 50 illustrated in the accompanying drawings, and particularly pointed out in the subjoined claims.

In the drawing, wherein similar reference characters designate corresponding parts 55 throughout the several views and in which

I have illustrated a skein holder suitable for use in practising the method of the invention and a skein as wound thereon—

Figure 1 is a side elevation showing the holder in position for the thread to be 60 wound thereon;

Fig. 2 is a top plan view;

Fig. 3 is a similar view showing the thread wound upon the holder.

Fig. 4 is a top plan view illustrating the 65 relative position of the parts of the holder when the skein is to be removed.

Fig. 5 is a detail sectional view taken on the line 5—5 of Fig. 2;

Fig. 6 is a diagrammatic view illustrating 70 the method of looping or winding the thread upon the holder to form the skein;

Fig. 7 is a similar view showing an intermediate point in the separation of the skein loops; and

Fig. 8 is a diagrammatic view showing the superposed loops completely separated to form a single loop.

Referring in detail to the drawing, 5 designates the body of the skein holder, 80 which, as shown, is of channel form in cross section and includes the side flanges 6 integrally connected by the body plate 7. The flanges 6 extend beyond one end of the plate 7 and terminate in the angularly disposed arms 8 which are recessed or bifurcated as at 9. The plate 7 is provided with spaced openings 10 to receive suitable fastening elements whereby the holder may be securely fixed upon one of the links of an 90 endless chain or other carrier of a skein winding machine.

The skein holding member 11 consists of a plate 12 having an angularly bent flange 13 extending along one of its longitudinal edges. This flange, at one end of the plate 12, is formed with an angularly disposed arm 14 which is bifurcated or recessed as at 15. The flange 13 is arranged closely adjacent to the inner face of one of the side 100 flanges 6 on the body member 5 and the arm 14 is pivoted as at 16 to the arm 8 on the flange 6. It will be observed that the bifurcation 15 of the arm 14 is not obstructed by the arm 8 but projects beyond the edge of 105 the latter arm.

A loop supporting element 17 is fixed to the other end of the plate 12 and is disposed at the inner edge thereof in a plane at right angles to the plane of said plate. 110

This element may be of any desired length, but as indicated in the drawing is preferably about twice the length of the body member 5. This element 17 at its free end is notched or bifurcated as shown at 18 and adjacent to said notch a longitudinally extending cavity or recess 19 is formed in one edge of said element for a purpose which will be hereinafter explained.

10 The body member 5 and the loop forming element 17 are normally held against relative pivotal movement by means of a latch dog 20 which is pivoted at 21 upon an angular extension 22 formed on one of the flanges 15 6 of the body member. This dog is adapted to engage a shoulder 23 formed on the end of the flange 13 and is yieldingly held in such engagement by means of a spring 24, one end of which is fixed to the flange 6 20 by the screw 25, while its other end is engaged with the angularly disposed lug 26 formed on the latch dog 19.

In practice, a plurality of the skein holding devices, as above described, are mounted, 25 in spaced relation with each other, upon the links of an endless chain, which constitutes a part of a skein winding mechanism. An intermittent movement is transmitted to this chain and the skein holding devices are successively brought to a substantially horizontal position at the upper end of the vertically disposed chain as seen in Fig. 1 of the drawing. The thread is carried and looped upon the parts of the holding devices by 30 means of a suitably actuated flier, but in so far as the subject matter of the present application is concerned, the winding operation may be performed by hand. I have 35 diagrammatically illustrated in Fig. 6 a method of winding a skein according to the principle of the present invention. In this figure A and B respectively indicate the spaced bifurcated arms 8 of the skein holder, while C indicates the bifurcation or notch 40 45 18 in the end of the element 17.

The improved method of winding skeins is practised as follows: At the start of the winding operation the thread or yarn T is first engaged with the supporting point 50 B and drawn through the notch 9 to the outside of the arm 8. The thread is now drawn longitudinally of the element 17 and passed laterally around the point C. This longitudinal thread strand c constitutes one side of a main or primary loop. At the point C the thread is drawn from the inner side of the element 17 through the notch or recess 18 to the outer side of said element, as at a, and extended longitudinally thereof, 55 and then inwardly around the point B. The thread is then returned along the inner side of the element 17 as at a' and again passed through the notch or recess 18 to the outer side of said element. The thread is now 60 65 70 75 80 85 90 95 100 105 110 115 120 125 130 drawn to the inner side of the point A, as

indicated at b, and then outwardly thereof and from this point A is returned upon itself and drawn through the notch or recess 19 in the top of the element 17, and again around the point C, as shown at b'. The thread is then extended longitudinally and again engaged around the point A and brought inwardly therefrom to the point of beginning. This latter strand of the thread, designated c' constitutes the other side of the main or primary loop. It will thus be seen that in the winding operation the thread T is formed into two intermediate or subsidiary loops comprising the strands a, a' and b, b', respectively, before the main or primary loop consisting of the strand c, c' is completed. It will thus be seen that the improved skein winding method of the present invention comprises partially forming a main or primary loop, then forming a plurality of intermediate or subsidiary loops within the circuit of the main or primary loop and finally completing the main or primary loop.

The winding operation above described is continued until the desired length of thread has been wound upon the holder into a skein in which a series of separate and distinct loops are formed with the loops arranged in superposed relation. It will, of course, be understood that the number of supporting points for the skein loops may be multiplied to form as great a number of loops in the skein as may be desired.

After the skein has been wound upon the holder, as above explained, in the next intermittent movement of the chain or carrier the holder with the skein thereon will be positioned at one side of the upper sprocket wheel. While in this position the attendant operative may now easily slip a tubular paper band 30 over the end of the element 17 and over the strand loops to approximately the position indicated in Fig. 4. In the continued intermittent movements of the chain, the holder is finally brought to a position where the latch dog 20 will be automatically engaged and released from its locking position with relation to the holder 23. At the same time a part is engaged in the notch or bifurcation 15 of the arm 14 and the loop supporting member 11 carrying the element 17 is swung laterally and outwardly in a horizontal plane to a position at right angles to its former position with respect to the chain, as also seen in Fig. 4. In the movement of the element 17 to the latter position, the tension of the skein loops upon the bifurcated arms 8 is slightly loosened so that the loops may be readily disengaged from said arms in the removal of the skein from the holder, which latter operation may be accomplished either automatically or by hand. There is a natural tendency of the yarn or thread, and particularly of coarse

5 **yarns, to twist upon itself when the individual strands of the skein are separated. I have found that the above described series of winding operations in the formation of the skein effectually eliminates this twisting tendency of the thread or yarn so that when the skein loops are separated, the thread will not twist at spaced intervals whereby the possibility of entanglement of the thread**

10 **strands with each other from this cause is obviated. The several superposed series of skein loops may be very easily separated into a single loop, as indicated in Figs. 7 and 8. This separation may be readily effected by**

15 **simply grasping the thread strands at the points of beginning and ending of the formation of the main or primary loop *c, c'*. The side portions of this main loop are then moved laterally away from the ends of the**

20 **intermediate or subsidiary loops which were wound around the points A and B respectively, and these ends of the intermediate or subsidiary loops are moved away from each other, as indicated in Fig. 7. The several**

25 **loops may then be straightened out so that a single continuous loop made up of a multiplicity of strands is produced as seen in Fig.**

30 **8. While I have referred to the separation of the several skein loops with some particularity, it is not necessary to individually grasp and separate the several loops, but by simply grasping the several strands of the main or primary skein loop firmly and shaking or snapping the skein, the several loops**

35 **will open up into the single loop form illustrated in Fig. 8.**

The improved method of skein winding described above possesses several features which commend it. The formation of the

40 **intermediate or subsidiary loops within the circuit of the main or primary loop eliminates the inherent tendency of several kinds of thread or yarn to twist upon itself at spaced intervals along the length of the**

45 **thread or yarn strand. Moreover, the formation of the intermediate or subsidiary loops within the circuit of the main or primary loops results in a skein (which forms the subject-matter of my copending application,**

50 **Serial No. 395,309, filed July 10, 1920) which may be put on the market and used in the condition or form in which it comes from the skein winding machine. In this form or condition the skein may be unwound without**

55 **entanglement and any desired length of strand drawn therefrom; or the skein may be unfolded by separating the intermediate or subsidiary loops from the main or primary loops to form a skein composed of a**

60 **series of simple loops in which condition the skeins, as put on the market at present, are used. Thus, the improved method of skein winding produces a skein which may be used in the same manner in which the**

65 **skeins produced by the methods now in practice are used. Moreover, this skein has the advantage of being used in the condition in which it comes from the skein winding machine, which is not the practice with the usual and common form of skein now on the market, and produced by the present methods of skein winding.**

70 **It will be understood that the method of skein winding of the present invention is not to be restricted to the winding of a skein about three fixed points, nor to the winding of skeins about spaced supports at one end and single supports at the other, inasmuch as the invention can be practised by winding the skein about a plurality of fixed supports at one end and a plurality of fixed supports at the other end. The generic principle of the invention comprehends the various specific methods comprising partially winding a main or primary loop, winding a plurality of intermediate or subsidiary loops within the circuit of the main or primary loop, and then completing the main or primary loop to produce the desired skein.**

75 **Having thus described the invention what I claim as new is:—**

80 **1. A method of winding skeins which consists in winding a thread about a plurality of supports to form a main or primary loop about all the supports and a plurality of intermediate or subsidiary loops about some of the supports.**

85 **2. A method of forming skeins which consists in winding the thread to form therein a primary loop and a plurality of subsidiary loops, spaced apart at one of their ends and superposed upon each other at their other ends, and finally extending the thread between the spaced ends of said subsidiary loops to close the primary loop.**

90 **3. A method of winding skeins which consists in partially forming a main or primary loop, then forming within the circuit of the main or primary loop a plurality of intermediate or subsidiary loops, and finally completing the main or primary loop.**

95 **4. A method of forming a skein which consists in winding a thread around spaced supports to form a series of multi-strand relatively short loops therein, the loops in one series being arranged in superposed relation to each other and to the loops in the other series, said loops being readily separable to produce a single multi-strand loop of a length equal to the combined length of the series of short loops.**

100 **5. A method of forming a skein which consists in winding a thread around spaced supports to form a series of multi-strand relatively short loops therein, the individual strands of the respective loops being disposed in superposed relation to each other and the strands of one loop being also disposed in intersecting superposed relation to**

the strands of the adjacent loop, said series of loops being readily separable to produce a single multi-strand loop of a length equal to the combined length of a series of short loops.

6. The method of forming skeins which consists in winding a thread to first form one end and one side of a primary loop, then forming within the circuit of the primary loop a plurality of subsidiary loops in the thread and finally returning the thread to the starting point to form the other side of the primary loop and thereby close the latter loop.

15 7. The method of forming skeins which consists in winding a thread around spaced supports to form a series of multi-strand loops, the individual strands of the respective loops being disposed in intersecting superposed relation with each other and the strands of one loop being disposed in intersecting relation with the strands of the adjacent loop.

8. The method of forming skeins which 25 consists in winding a thread around spaced supports to first form one end and one side of a primary loop, then forming a series of subsidiary loops in the thread, the individual strands of the loops of each series being in intersecting relation with each other and with the individual strands of the other loops, and finally returning the thread to

the starting point to form the other side of the primary loop, thereby closing the latter loop.

35 9. The method of forming skeins which consists in winding a thread around fixed supports to form first two sides of a primary loop, then winding the thread to form a plurality of subsidiary loops within the 40 circuit of the primary loop and finally completing the primary loop.

10. The method of forming skeins around three fixed supports which consists in winding a thread in such manner as to partially 45 form a primary loop, then forming a plurality of subsidiary loops by winding the thread from one of the supports alternately around two supports and finally completing the primary loop.

50 11. The method of forming skeins which consists in winding a thread around three fixed supports so as first to partially form, around the outsides of the supports, a primary loop, then forming about two of the 55 supports, a subsidiary loop, next forming about one of these supports and the third support, a second subsidiary loop, and finally completing the primary loop around the outsides of the supports.

60 In testimony that I claim the foregoing as my invention, I have signed my name hereunder.

MAX O. CLAUSS.
